UNITED STATES PATENT OFFICE.

RICHARD G. TURNER, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

ELECTRICAL WARP STOP MOTION FOR LOOMS.

Application filed December 21, 1927. Serial No. 241,672.

This invention relates to improvements in electrical warp stop motions more particularly adapted for use on looms and it is the general object of the invention to provide an improved form of electrically operating warp stop motion which shall indicate visually the location of the warp fault.

It is an important object of my present invention to provide a plurality of spaced wires, prongs or needles such as are presented by card clothing and to arrange said needles in groups of different electrical potentials, the needles or prongs of the two different groups being close enough to be bridged by a raised drop wire.

It is a further object of my invention to provide means for raising a fallen drop wire and holding the same in raised position not only to establish an electric circuit but also to indicate the location of the warp fault.

It is a further object of my invention to provide a flexible device to extend through slots provided in the upper ends of the drop wires and to give said flexible devices a quick whipping motion at periodic intervals so that any drop wire which may have fallen upon it will be shot upwardly and be lodged between the various wires located thereabove. It is sufficient for the purposes of the present invention if the flexible cord lies under a part of the fallen drop wire without necessarily passing through the slots.

With these and other objects in view which will appear as the description proceeds, my invention resides in the combination and arrangement of parts hereinafter described and set forth in the claims.

In the accompanying drawings wherein I have shown a convenient embodiment of my invention,

Fig. 1 is a top view of a portion of a loom having my invention applied thereto,

Fig. 2 is a rear elevation taken in the direction of arrow 2, Fig. 1, and showing the flexible device in slackened position in full lines,

Fig. 3 is a detailed end elevation taken in the direction of arrow 3, Fig. 2,

Fig. 4 is an enlarged vertical section taken on line 4-4 of Fig. 1,

Fig. 5 is an enlarged vertical transverse section taken on line 5-5 of Fig. 2, and

Fig. 6 is an enlarged vertical section on line 6-6 of Fig. 3.

While the invention set forth herein is applicable to any machine acting in conjunction with a series of warp threads, yet I have chosen to illustrate the same in connection with a loom and have indicated a loom frame 10 in which a bottom shaft 11 is caused to rotate by mechanism not shown but well understood. A warp beam 12 is mounted for rotation in the loom and supplies a warp W which is controlled by the various loom instrumentalities not shown herein. The warp passes over a whip roll 13 and then extends in a substantially horizontal plane toward the harnesses. The breast beam B is provided with so-called shipper mechanism including a shipper lever 14 received in a notch 15 formed in the right hand end of a slot 15' as viewed in Fig. 1 and an electromagnet 16 is positioned to act upon a lever 17 pivoted at 18 to the breast beam. The effect of said lever when actuated by the magnet is to move the shipper handle 14 out of the notch into the slot, a condition which is accompanied by stopping of the loom. A battery 19 is provided to supply the necessary energy for energizing the magnet 16 and said battery is connected to the magnet by a wire 20. The matter thus far described is either of common construction or does not enter specifically into my present invention, the electrical feature being merely illustrative as setting forth a convenient way of stopping the loom when the magnet 16 is energized.

In carrying my invention into effect I provide means whereby the battery may be electrically connected to the magnet whenever a fault occurs in one or another of the warp threads W and to this end I provide a pair of brackets 30, one at each side of the loom, and mount thereon a plurality of spaced separator bars 31 and also a guide bar 32 shown particularly in Fig. 5. I provide a plurality of drop wires 33 each provided in the upper portion thereof with a vertical slot 34 and having in the lower portion thereof another slot 35 to receive the guide bar 32, the upper end of slot 35 forming a supporting surface 36 which rests on the warp thread. It is to be understood that there is one drop wire for each of the warp threads W and that the drop wires are arranged in a bank extending across the warp threads and located between the separator bars 31 and held against turning about a vertical axis by

the guide bar 32. The warp threads support the drop wires and hold them in normal raised position.

My present invention is designed for co-operation with a device for raising a fallen drop wire to a position where the latter may complete an electrical circuit to effect stopping of the machine to which the warp stop motion is applied, and in carrying this part 10 of my invention into effect I provide one of the brackets 30, the one at the right as shown in Figs. 1 and 2, with a screw or stud 40 and support the right hand end of a flexible element or cord 41. The other end of said cord 15 extends over a sheave 42 pivotally mounted on a fixed stud 43 which may be carried by the left hand bracket 30. The vertical portion of the cord is received by an eye bolt 44 mounted on a lever 45 pivoted as at 46 to a 20 larger lever 47. Lever 47 is pivoted as at 48 to the loom frame and carries an adjustable stop screw 49 to engage a fixed stop 50. A roll 51 rotatable on the lever 45 engages a spiral cam 52 secured adjustably as to angular 25 position on bottom shaft 11. The cam has a high point 53 and an abrupt fall 54 to permit the lever 47 to fall quickly when the shaft 11 reaches a predetermined angular position. The stop pin 55 on lever 47 holds the 30 roll in proper position to cooperate with the cam and if the loom be turned backwardly lever 45 can turn about its axis against the action of a torsion spring 56 interposed between stud 46 and lever 45 and tending to 35 hold the latter against the pin 55.

During the operation of the loom the bottom shaft turns every second pick of the loom so that the cam 52 operates through the lever 47 to cause a sudden straightening of the 40 cord 41 so that the same moves from the curved form shown in full lines to a straight position shown in dotted lines in Fig. 2. Should a drop wire be fallen at the time the 45 cord is straightened said drop wire will be engaged by the cord and given a quick upward movement to move above the other drop wires.

I have shown herein one particular means for raising a fallen drop wire but it is to be understood that the electrical part of the device set forth herein operates independently 50 of the mechanism which raises a fallen drop wire and is dependent merely upon the fact that the drop wire is raised without reference to the manner of its raising.

Stands 60, one at each end of the loom, support a plate 61 to the underside of which may be secured an inverted channel member 62 made preferably of insulating material such 60 as fiber. A strip of card clothing 63 may be secured to said channel member 62 as shown in Fig. 5. The teeth or needles 64 which are carried by the card clothing are arranged in two different groups. As shown in Fig. 5 one group A is formed of two staggered sets

of inverted U-shaped wires, one set 65 overlapping the other section 66 by a small amount to permit the passage of an electric conducting wire 67. This wire is in electrical contact with all the wires 65 and 66 and 70 is connected by wire 68 to the magnet 16. The other group C of wires is similarly formed and is associated with an electric wire 69 which may be connected by wire 70 to that side of the battery 19 which is opposite 75 the wire 20.

It is to be understood that the wires of the card clothing are all in contact with the electric conducting wires, the wires of one group being connected to one side of the circuit 80 and the wires of the other group being connected to the opposite sides of the circuit and that the groups are disposed as shown in Fig. 5 so that a drop wire which is shot upwardly by the cord 41 will be required to engage at 85 least one wire of each group.

There will be a pair of groups of needles 64 for each bank of drop wires and the principle illustrated in connection with Fig. 1 can be extended to a loom provided with several banks of drop wires. The closing of the circuit is facilitated by the shape of the teeth on needles 64. It will be seen by referring to Fig. 4 that said wires extend through the cloth 63 in a direction substantially perpendicular to the cloth but that the lower ends are bent or inclined slightly as indicated at 71. I have found that this slight bend, which is characteristic of most forms of card clothing and need not be made especially for the application shown herein, assists in bringing about more intimate electrical contact between the wires 64 and the upper part of the raised drop wire.

The teeth or needles 64 hold a drop wire 105 which has been raised into engagement with them to indicate the location of the warp fault.

From the foregoing it will be seen that I have provided an electrical warp stop motion 110 wherein a large number of small wires or prongs are arranged in two electrically separated groups placed sufficiently close together, however, so that the groups may be connected together electrically by a raised drop wire. 115 It will also be seen that I have provided a warp stop motion employing a flexible cord device which is effective to raise a fallen drop wire at selected times, means being provided to stop the loom under these circumstances. 120 It will be seen that the cam which controls the whipping of the cord 41 is angularly adjustable on the bottom shaft so that the time of stopping in the cycle of the loom may be adjusted as desired. It will also be seen that 125 the prongs or wires of the card clothing hold the raised drop wire to indicate the location of the warp fault.

While I have shown herein card clothing as the means for establishing electrical con- 130

tact with the raised drop wire yet I do not wish to be limited to the material which is definitely recognizable in the trade by the term card clothing as any equivalent construction and disposition of wires and needles will accomplish the same result as set forth herein.

Having thus described my invention it will be apparent that changes and modifications may be made therein by those skilled in the art without departing from the spirit and scope of the invention and I do not wish to be limited to the details herein disclosed, but what I claim is:

1. In an electrical warp stop motion for looms having a bank of drop wires supported normally in raised position by the warp threads together with means for raising a drop wire corresponding to a broken warp 70
20 thread to a position above the other drop wires, a pair of spaced groups of drop wire holding elements, the elements of each group being electrically connected together and being insulated from the elements of the 75
25 other group, the elements of both groups being sufficiently close together to be bridged by and electrically connected through a raised drop wire, and means to stop the loom 80 when a drop wire is raised into electrical contact with elements of both groups.

2. In an electrical warp stop motion for looms having a bank of drop wires supported normally in raised position by the warp threads together with means for raising a 85
25 drop wire corresponding to a broken warp thread to a position above the other drop wires, card clothing located above the drop wires normally supported by the warp threads, the prongs of said card clothing 90
40 being separated into two groups, the prongs of each group being electrically connected to each other and insulated from the wires of the other group, said groups being close enough together to have electric contact 95
45 with a raised drop wire, and electromagnetic means to stop the loom when a raised drop wire electrically connects the groups of wires together.

3. In an electrical warp stop motion for looms having a bank of drop wires supported normally in raised position by the warp threads together with means for raising a drop wire corresponding to a broken warp 100
50 thread to a position above the other drop wires, card clothing located above the normal position of the drop wires supported by the warp threads, the prongs of the card clothing being separated into two groups, the prongs of each group being electrically connected together and insulated from the wires of the other group, said prongs depending from the card clothing and having the lower ends inclined to a vertical line, a drop wire 105
55 which is raised above the other drop wires of the bank engaging prongs of both groups to

connect said groups together electrically, and electromagnetic means to stop the loom when said groups are electrically connected together.

4. In a warp stop motion for a loom having a bank of drop wires normally supported in raised position by the warp threads of the loom, a normally slack flexible element extending under a portion of each of the drop wires, means to tighten the flexible element 75
70 to cause the same to give a quick upward movement to a fallen drop wire supported temporarily by the element, and means to engage and hold in raised position any drop wire which may be moved upwardly by the so element.

5. In a warp stop motion for a loom having a bank of drop wires normally held in raised position by the warp threads in the loom, a normally slack flexible element extending under a portion of each drop wire, a drop wire holding device located above the warp threads and above the normal position of the drop wires supported by the warp threads, and means to tighten the flexible element 85
80 to cause the latter to give the fallen drop wire supported thereby a quick upward movement toward said holding means, whereby the location of the warp fault may be indicated visually.

6. In a warp stop motion for a loom having a bank of drop wires normally supported in raised position by the warp threads, a normally slack flexible element extending under a portion of each of the drop wires, and means whereby said flexible element may be tightened to give a quick upward movement 100
105 to a fallen drop wire supported temporarily by the element to indicate the location of the warp fault.

7. In a warp stop motion, a bank of drop wires each provided with a slot in the upper portion thereof, a flexible element extending through the slots of the drop wires and normally in slack position, means to periodically 110
115 tighten said flexible element to render the same taut to impart an upward movement to a fallen drop wire, and means to effect a change in the machine to which the stop motion is applied when the drop wire is moved to raised position by the tightening of the flexible element.

8. In a warp stop motion for a loom having a plurality of drop wires each of which is provided with a slot and the drop wires so arranged that the slots are in substantial alignment, a normally slack flexible element extending through the aligned slots of the drop wires, means to tighten said element at periodic intervals so that said element will 120
125 impart an upward movement to any drop wire which may be in fallen position and temporarily supported by said element, and means to stop the loom when any drop wire has been raised by the flexible element.

9. In a warp stop motion to control the operation of a machine, a bank of drop wires supported normally by the warp threads, a flexible device normally slack and lying under a portion of each of the drop wires, means to tighten the flexible element to cause the same to engage and lift a fallen drop wire, and means to stop the machine when the drop wire is lifted by said flexible element.
10. In a warp stop motion for a loom having a rotating shaft and a group of drop wires supported normally in raised position by the warp threads, a flexible element normally slack and extending under a portion of each of the drop wires, means operated from the shaft to cause a periodic tightening of the flexible element to cause the latter to raise a fallen drop wire to a position above the other drop wires, and means to stop the loom when a fallen drop wire is raised by said flexible element.
11. In a warp stop motion for a loom having a rotating shaft, a bank of drop wires normally supported in raised position by the warp threads, a cam mounted in adjusted angular position on said shaft, a flexible element normally slack and extending under a portion of each of the drop wires, connections between said flexible element and the cam to tighten said flexible element at periodic intervals in the operation of the loom, the particular time and the cycle of the revolution of the loom being determined by the angular position of the cam relatively to the rotating shaft, and means to stop the loom when the flexible element engages a fallen drop wire to raise the same at the time the flexible element is being tightened.

In testimony whereof I have hereunto affixed my signature.

RICHARD G. TURNER.
